DESIGN FOR A TEXTILE FABRIC OR SIMILAR ARTICLE

Roger Megroz, Bronxville, N. Y., assignor to J.
Oltarsh, New York, N. Y.

Application December 5, 1933. Serial No. 49,958

Term of patent 3½ years

To all whom it may concern:

Be it known that I, ROGER MEGROZ, a citizen of the United States residing at 9 Southway Street, Bronxville, New York, have invented a new, original, and ornamental Design for a Textile Fabric or Similar Article, of which the following is a specification, reference being had to the accompanying drawing, forming a part thereof.

The figure is a plan view of a textile fabric showing my new design. The dot and dash lines on the drawing outline substantially a design unit which unit is repeated in regular succession as indicated by the extensions beyond the unit boundaries.

I claim:

The ornamental design for a textile fabric or similar article as shown and described.

In testimony whereof I have signed this specification.

ROGER MEGROZ.
